LOUIS M. ASPINWALL, OF PITTSBURGH, PENNSYLVANIA, ASSIGNOR TO WESTINGHOUSE ELECTRIC & MANUFACTURING COMPANY, A CORPORATION OF PENNSYLVANIA.

BROACHING DEVICE FOR TORPEDOES.

1,323,347.

Specification of Letters Patent.

Patented Dec. 2, 1919.

Application filed April 18, 1919. Serial No. 291,036.

To all whom it may concern:

Be it known that I, LOUIS M. ASPINWALL, a citizen of the United States, and a resident of Pittsburgh, in the county of Allegheny and State of Pennsylvania, have invented a new and useful Improvement in Broaching Devices for Torpedoes, of which the following is a specification.

My invention relates to broaching devices for torpedoes and it has for its object to provide apparatus of the character designated that shall in no way interfere with the adjustment of the depth rudder during the travel of the torpedo but which shall effectively move the depth rudder to the broaching position at the end of the torpedo travel, irrespective of the setting that the control mechanism tends to give to the depth rudder at this time.

20 The single figure of the accompanying drawing is a side view of the after-body of a torpedo, partially broken away and showing, in diagrammatic form, the elements of a broaching system embodying my invention.

25 In the control of a torpedo, it is the usual practice to provide a horizontal rudder for the control of the running depth, placing this rudder under the control of a pendulum, responsive to the departure of the torpedo from even keel and also to the control of a pressure diaphragm sensitive to changes in the degree of submergence, whether on an even keel or not. Upon reaching the end 30 of its travel, as when used in experimental trips, it is desirable that the torpedo shall be recovered for re-use, but, if, when the propeller force is exhausted, the rudder is depressed, the torpedo goes to the bottom 35 and recovery is difficult. It has, therefore, been proposed to employ broaching devices which cause the horizontal rudder to be thrown to the "up" position after a predetermined torpedo travel, irrespective of 40 the setting of the control devices at this time.

45 Certain of the broaching devices that have been proposed have required that the immersion steering mechanism shall work against a broaching spring throughout the entire run. This has required the use of heavy and powerful steering mechanism, with consequent loss of sensitiveness.

50 In accordance with the present invention, I provide a lever, in the linkage connecting

the controlled mechanism with the horizontal rudder, with a floating fulcrum. A broaching spring normally tends to throw this fulcrum to such position that the rudder is placed in the broaching position, irrespective of the setting of the steering mechanism. Rather than oppose this broaching spring by the steering mechanism, however, I oppose it by a solenoid or other electrical translating device that is energized when the torpedo is fired. A circuit-opening mechanism is provided that is operative from the propeller shaft, or otherwise, to open the energizing circuit of this translating device after a predetermined 70 torpedo travel. The effect of the translating device, when energized, has been to overcome the broaching spring and to place the floating fulcrum in such position that the control mechanism could function 75 properly, but the deenergization of the translating device permits the broaching spring to move the fulcrum to the other position, thus causing the torpedo to broach.

Referring to the drawing for a more detailed understanding of my invention, I show the after-body of a torpedo at 5, propulsion being effected by the usual oppositely rotating propellers 6 and 7 driven by shafts 8 and 9. A horizontal or depth rudder 10, of usual form, is provided and is coupled to a control mechanism 11 through links 12 and 13 and a lever 14. The mechanism 11 embodies a pendulum 15 and a depth diaphragm 16 and is enabled to control the depth of immersion of a torpedo through the rudder 10 when the fulcrum 17 of the lever 14 is moved to the extreme left-hand position by a solenoid 18 having an adjustable stop 19. A broaching spring 20 opposes the pull of the solenoid 18 and tends to move the fulcrum 17 to the right, under which conditions the rudder 10 is thrown upwardly to broach the torpedo, irrespective of the setting of the device 11.

100 A rotatable drum 21 is provided with a conducting segment 22, partially surrounding its periphery, and contact brushes 23 and 24 bear upon this segment. The energizing circuit for the solenoid 18 is closed 105 through these brushes and the segment from a current source 25. The drum 21 is driven at low speed from the propeller shaft 9, as by a double-worm reduction 26, the arrangement being such that the brushes 110

23—24 leave the segment 22 after a predetermined torpedo travel, such, for example, as 4000 yards, determined by the number of propeller revolutions.

5 Having thus described the arrangement of a system embodying my invention, the operation thereof is as follows. At the time of firing, the brushes 23 and 24 bear upon the segment 22 and the energizing circuit 10 for the solenoid 18 is closed. The fulcrum 17 is moved to the extreme left-hand position by the solenoid 18, and steering linkage is in such position that the control device 11 may function properly and accurately. At 15 the conclusion of the desired travel, the brushes 23 and 24 leave the segment 22 and the solenoid 18 is deenergized, whereupon the broaching spring 20 pulls the fulcrum 17 to the right, throwing the rudder 10 to 20 the broaching position, irrespective of the setting of the mechanism 11. Particular attention is directed to the fact that the steering mechanism 11 is not required to overcome the broaching spring 20 during 25 the travel of the torpedo and thus the device 11 may be of great sensitiveness and delicacy. Furthermore, the fulcrum 17 is held in a firm and positive manner at a readily adjustable position, during the travel 30 of the torpedo, so as to in no way interfere with the proper adjustment of the horizontal rudder.

While I have shown my invention in its preferred form, it will be obvious to those 35 skilled in the art that it is not so limited, but is susceptible of various minor changes and modifications without departing from the spirit thereof, and I desire, therefore, that only such limitations shall be placed 40 thereupon as are imposed by the prior art or are specifically set forth in the appended claims.

I claim as my invention:

1. In a broaching system for torpedoes, 45 the combination with a horizontal rudder, of an operating linkage therefor, said linkage including a lever having a floating fulcrum, means normally tending to throw said fulcrum to a position causing a broaching 50 setting of said rudder, and means for overcoming said broaching means and holding said fulcrum in another position during a predetermined range of travel of the torpedo.

55 2. In a broaching system for torpedoes, the combination with a horizontal rudder, of a control linkage therefor, control means for operating said linkage and rudder to maintain said torpedo at a predetermined 60 depth, said linkage including a lever having a floating fulcrum, means for maintaining said fulcrum at one position during a predetermined range of travel of the torpedo, such that said control means is operative, 65 and means for then shifting said fulcrum

to another position, such that said rudder is thrown to the broaching position, irrespective of the setting of said control means.

3. In a broaching system for torpedoes, 70 the combination with a horizontal rudder, of a control linkage therefor, control means for operating said linkage and rudder to maintain said torpedo at a predetermined depth, said linkage including a lever having a floating fulcrum, a spring tending to 75 throw said fulcrum to such position as to move said rudder to the broaching position, irrespective of the adjustment of said control means, an electrical translating device capable of overcoming said spring and of 80 moving said fulcrum to such position that said control means may properly function, an energizing circuit for said translating device that is closed at the firing of the torpedo, and means for opening said circuit 85 after a predetermined range of torpedo travel.

4. In a broaching system for torpedoes, 90 the combination with a horizontal rudder, of a control linkage therefor, control means for operating said linkage and rudder to maintain said torpedo at a predetermined depth, said linkage including a lever having a floating fulcrum, a spring tending to 95 throw said fulcrum to such position as to move said rudder to the broaching position, irrespective of the adjustment of said control means, an electrical translating device capable of overcoming said spring and of 100 moving said fulcrum to such position that said control means may properly function, an energizing circuit for said translating device that is closed at the firing of the torpedo, and means for opening said circuit 105 after a predetermined number of revolutions of the torpedo propeller.

5. In a broaching system for torpedoes, 110 the combination with a horizontal rudder, of a control linkage therefor, control means for operating said linkage and rudder to maintain said torpedo at a predetermined depth, said linkage including a lever having a floating fulcrum, a spring tending to throw 115 said fulcrum to such position as to move said rudder to the broaching position, irrespective of the setting of said control means, a solenoid having a plunger and an adjustable stop member therefor, said plunger being connected to said fulcrum and said solenoid being capable of overcoming said 120 spring and of moving said fulcrum until the plunger reaches said stop, said control means being permitted to function properly in this position, an energizing circuit for said solenoid, said circuit being closed when 125 the torpedo is fired, and means for opening said circuit after a predetermined range of torpedo travel.

6. In a broaching system for torpedoes, 130 the combination with a horizontal rudder.

of a control linkage therefor, control means for operating said linkage and rudder to maintain said torpedo at a predetermined depth, said linkage including a lever having 5 a floating fulcrum, a spring tending to throw said fulcrum to such position as to move said rudder to the broaching position, irrespective of the setting of said control means, a solenoid having a plunger and an adjustable stop member therefor, said plunger being connected to said fulcrum and said solenoid being capable of overcoming said spring and of moving said fulcrum until the plunger reaches said stop, said control means 10 being permitted to function properly in this position, an energizing circuit for said solenoid, said circuit being closed when the torpedo is fired, and means for opening said circuit after a predetermined number of revolutions of a torpedo propeller.

7. In a torpedo broaching mechanism, the combination with a depth rudder, of a control mechanism therefor, and operative for the adjustment thereof for the maintenance of

the torpedo at a predetermined depth during 25 its range of travel, a broaching spring under strain upon a portion of the steering mechanism throughout the range of travel, and means other than said steering means for opposing said spring, said opposition being removed after a predetermined range of travel.

8. In a broaching device for torpedoes, the combination with a depth rudder, of control means therefor effective to control the 35 immersion of said torpedo throughout the range of travel thereof, a broaching spring under strain and operative upon said steering mechanism throughout the range of torpedo travel, a solenoid opposing and overcoming said spring throughout the range of torpedo travel, and means for deenergizing said solenoid after a predetermined range of torpedo travel.

In testimony whereof, I have hereunto 45 subscribed my name this 31st day of March, 1919.

LOUIS M. ASPINWALL.
